DESIGN FOR A COMBINED FLAG AND STAFF

Francis Frazier, Oakland, Calif.

Application August 8, 1938, Serial No. 79,177

Term of patent 7 years

To all whom it may concern:

Be it known that I, Francis Frazier, a citizen of the United States of America, residing at Oakland, in the county of Alameda and State of California, have invented a new, original, and ornamental Design for a Combined Flag and Staff, of which the following is a specification, reference being had to the accompanying drawing, forming a part thereof.

The figure is a front elevational view of the combined flag and staff, showing my new design.

I claim:

The ornamental design for a combined flag and staff, substantially as shown.

FRANCIS FRAZIER.
